P. H. BAXTER.

CHECK HEAD FOR PLANTERS.

APPLICATION FILED JULY 18, 1917. RENEWED DEC. 3, 1920.

1,390,748.

Patented Sept. 13, 1921.

UNITED STATES PATENT OFFICE.

PHILIP H. BAXTER, OF CORYDON, IOWA, ASSIGNOR TO DEERE & COMPANY, OF MOLINE, ILLINOIS, A CORPORATION OF ILLINOIS.

CHECK-HEAD FOR PLANTERS.

1,390,748.

Specification of Letters Patent. Patented Sept. 13, 1921.

Application filed July 18, 1917, Serial No. 181,384. Renewed December 3, 1920. Serial No. 428,151.

To all whom it may concern:

Be it known that I, PHILIP H. BAXTER, a citizen of the United States, residing at Corydon, in the county of Wayne and State 5 of Iowa, have invented certain new and useful Improvements in a Check-Head for Planters, of which the following is a specification.

This invention has relation to check row 10 corn planters, and has for an object to improve the check head in a manner to permit the check wire to be more quickly and conveniently threaded thereinto, thereby providing what may be termed a self-threading check head.

In addition to the foregoing my invention comprehends improvements in the details of construction and arrangement of the parts to be hereinafter more fully described and particularly set forth in the appended claims.

20 In the accompanying drawings in which similar and corresponding parts are designated by the same characters of reference 25 throughout the several views in which they appear;

Figure 1, is a view in side elevation of the right hand check head of a check row corn planter illustrating the embodiment therein 30 of my invention.

Fig. 2, is a view of the check head in end elevation,

Fig. 3, is a view thereof in plan.

With reference to the drawings, 10 indicates a pair of parallel spaced bars which extend transversely of the corn planter and which support the seed boxes and the check head indicated as an entirety at 11. The check head comprises a frame casting 40 formed with upwardly diverging curved arms 12, connected at their lower end by means of a connecting strip 13 which is enlarged as at 14 to provide a journal for the seed dropper shaft 15. The shaft is disposed transversely of the machine, parallel to the bar 10, and has fixedly mounted thereon an upwardly extending arm 16 which is bifurcated at its upper end to receive a fork 17 which is mounted upon a bolt 18 extended across the bifurcated portion of the said arm whereby to permit oscillatory movement of said fork in a plane which is parallel to and intersects the seed dropping shaft. As will be seen the fork may be disposed in a horizontal position when inopera-

tive and in a vertical position when operative.

The upper terminals of the arms 12 of the check head casting are formed with concaved extensions 19 which are located so as to direct their concaved portion outwardly to receive and guide the check wire. A pulley 20 is mounted adjacent each of said concaved extensions to coact with said extension in such a manner as to retain the check wire therein in the usual manner. The pulleys 20 are mounted upon a casting 21 in the nature of a yoke upon the terminals of which the pulleys are mounted, and which yoke is provided with a pair of trunnions 22 extending in opposite directions to fit in apertured ears 23 formed upon the upper terminals of the arms 12 of the check head casting. Thus, the pulley holder is mounted for oscillation in a vertical plane 75 from a position wherein the pulleys are located as described or for rotation in a horizontal plane, to a position wherein the pulleys are inverted from their former positions. The object of mounting the pulleys 80 for movement in this manner is to open the concaved extensions 19 so that the check wire may be inserted therein, the pulleys being subsequently moved to a position to inclose the wire in said concaved extension 85 and to securely retain the wire against displacement. To retain the pulley holder in its first mentioned position a latch 24 is provided, pivotally mounted as at 25 upon a gear 26 formed upon the check head casting 90 for engaging the intermediate portion of the pulley holder, the latch being held in such position by means of a spring 27 which is interposed between an extension 28 of the latch and the check head casting. The latch 95 may be readily disengaged by means of a rod 29 which extends from said latch to a point adjacent the driver's seat.

In order to guide and support that part of the wire which is adjacent the planter 100 while it is being moved (bodily, laterally, under tension) from or toward the machine I provide a guide extending laterally outward from the check head or frame. This guiding and supporting device comprises a lower element, indicated as an entirety by 31, and an upper element 30. The upper element comprises a bar 34 extending from transverse vertical planes in front of to transverse vertical planes in rear of those of 110

the fork. It is stationary relatively to the frame, to which it is secured rigidly by attaching devices such as arms 35 (integral with the part 34 at the bends 32), with 5 downwardly turned legs fastened to the check head. The front and rear bars, or attaching parts 35, are bent as at 37 so as to provide inclined parts 35^a which are extended inward and upward, and parts 35^b which 10 are extended outward and upward. The inner terminal parts or legs of the attachment bars 35 are secured to the inner faces of the arms 12 of the check head or frame by bolts 36.

15 The lower member 31 of the wire support and guide comprises a bar 39 which also extends from the front to the rear of the transverse vertical planes of the fork and is stationary relatively to the frame. It is attached thereto by arms 40 (integral with bar 39) terminating in vertical legs which are secured to the check head or frame by the devices at 41. The arms 40 are, at 42, bent so that their outer parts 40^a extend downward, outward and longitudinally of the machine, there being bends at 38 at the ends of the bar 39. The inner parts 40^b of the lower element are positioned horizontally. The bends at 37 and 42 are in approximately 25 the same vertical longitudinal planes.

The outer parts of the lower member and of the upper member of the guide and support device diverge outward from the vertical plane of the bends and also diverge inward, when observed on horizontal lines longitudinal of the machine. The bars 34 and 39 are both approximately parallel to said longitudinal lines but the bar 34 is positioned, laterally, away from the frame considerably farther than is the lower bar 39.

40 A passageway for a relatively long section of the wire is thus provided through which it can be moved bodily laterally in either direction, its passage having an inwardly narrowing entrance way (between the outer parts of the guide elements) extending to the bends 37, 42 and an inwardly widening part extending from the throat of the bends toward the frame. The fork 17 is formed of 45 a pair of spaced parallel bars 43 which are bent away from each other to form the arms 43^a and 43^b, and it will be seen from Fig. 2 that when the fork is disposed in a horizontal or inoperative position, the diverging 50 portions of said fork lie substantially parallel to the diverging outer ends of the guides 30 and 31, so that any object such as a wire which is caused to enter laterally between the guide elements 30 and 31 will also 55 be compelled to pass between the diverging ends of said members 43 of the fork so as to enter said fork.

60 When using a planter having my improvements the dropping of the wire at the end 65 of a row is accomplished quickly and in sub-

stantially the same way that is now followed in using standard machines provided with check heads, such as are herein shown. That is to say, the operator by means of the usual cord and while in his seat, opens the 70 catch 24 and releases the swinging parts of the wire holding system, the rollers 20 and their carrier 21. Under the tension of the wire these swinging parts are carried from the positions shown in Figs. 1 and 3 to that 75 shown in Fig. 2, the fork 17 also being carried downward and outward by the downward and laterally moving, tensioned wire. The wire after escaping from the pulleys 20 impinges on the lower element of the guide 80 and holder and is shed from the inclined outer part and from its seat in the fork, over the bar 39, to the ground.

85 After the operator has turned the machine and is ready for the return traverse across the field it is then necessary to move the check wire and its ground stake from its old location to the new location and to restore the wire to its normal working position in the holder provided for it by the 90 parts on the check head or frame.

95 With my mechanism it is not necessary for the operator to approach the check head to place the wire in operative position or is it necessary for him to resume his seat and 100 then by foot operated or manual devices place the wire in position. All that is required is that after pulling the check wire stake from its old location in the ground the operator, as he moves the check wire and the stake toward the new location at which the stake is to be reset (which is directly in the rear of the middle of the planter), should hold the check wire in such position 105 that it will enter the passageway formed between the upper and lower guides 30 and 31, respectively, as he passes back of the check head. Then as the point is reached where the stake is to be reset the operator 110 with the exertion of a quick longitudinal pull on the check wire gives it the proper tension preliminary to setting the ground stake. The longitudinal pull causes the wire to complete its travel inwardly through the guiding means 30 and 31, and the wire in 115 its inward movement carries with it the check fork 17 and the pulleys 20, they, as shown, lying in the path that the wire is constrained to follow.

120 When the check wire moves inwardly in response to the tensioning impulse above described it follows the parts 35^b and 35^a of the upper guide (in some cases resting more or less on the support parts 40^b and 40^a). The check fork 17 is caused to swing upward 125 around its pivot under the inward lateral pressure of the wire and the carrier bar 21 is also caused to rock upwardly owing to its engagement with the arm 43^b of the fork, or if preferred, the parts can be arranged for 130

the check wire to impinge upon the pulleys 20 or the carrier bar 21 and rock them into closed position. The quick inward lateral pressure of the wire due to the longitudinal pull acts upon the fork 17 and the pulleys 20 (upon the latter through the pulley bar 21) to snap them into the position shown in Figs. 1 and 3 where they are locked by the catch 24 engaging the bar under the action 10 of spring 27.

All of these matters have been accomplished without any movements of the guide elements 30, 31 relatively to the frame, both the lower and the upper element remaining 15 fixed in position. The wire through the force of tension exerted upon it has caused all of the movements of the parts from the positions of wire discharge to their normal working positions, and has caused an automatic locking of these parts in the latter positions.

If at any time it is desired to use the planter with the ordinary parts, the bolts or fasteners 36 and 41 which attach the 25 check wire holder and guide can be readily removed and the guide taken off, the remaining parts then constituting a complete operative holder and guide of the standard sort.

30 To persons acquainted with the use and operation of check row corn planters, the saving of time and labor may be effected by the use of this improvement, will be immediately apparent.

35 While I have illustrated and described my invention with some degree of particularity, I realize that in practice various alterations thereover may be made, and I therefore desire to reserve the right and privilege of 40 changing the form of the details of construction, and of altering the arrangement of the correlative parts without departing from the spirit of the invention or the scope of the appended claims.

45 Having thus described my invention what I claim as new and desire to secure by Letters Patent is:—

1. In a planter, the combination with the 50 check head frame, a seeder actuating device, a fork for operating said device movable from its normal working position to a wire-discharging position, and means supplemental to the fork for normally holding a check wire in its working position, of a support rigid with and extending laterally from the frame to support a section of the check wire while it is moving bodily laterally from or toward said normal working position, said support 55 being positioned normally below the passageway through which the wire passes when moving laterally as aforesaid, and said support extending longitudinally of the machine continuously from a point in front 60 of the fork to a point in the rear thereof, and

means for limiting the upward movement of the check wire away from said support when the wire is so moving.

2. In a planter, the combination with the check head frame, a seeder actuating device, 70 a fork for operating said device movable from its normal working position to a wire-discharging position and means supplemental to the fork for normally holding a check wire in its working position, of a wire guide rigid with and extending laterally from the frame to limit the upward rise of a section of the check wire while it is 75 moving bodily laterally from or toward said normal working position, said guide being positioned in lines above the path normally followed by said wire section and extending longitudinally of the machine continuously from a point in front of the fork to a point in rear thereof and arranged to guide said 80 section into the fork when the latter is in its wire-discharging position.

3. In a planter, the combination with the check head frame, the seeder actuating device, the fork for operating said device and 90 movable from a normal working position to a wire-discharging position, and movable means supplemental to the fork for holding the check wire in normal working position, of a laterally projecting guide held stationary relatively to the frame and having an upper element and a lower element both extending longitudinally from points in front to points in rear of the fork and respectively positioned as described relatively to the 95 working positions of the wire and of the fork as set forth whereby said guide causes a section of the wire while moving laterally inward toward its working position and under longitudinal tension exerted at a distant point at an angle to the longitudinal lines of the machine, to enter the fork when the latter is in its wire-discharging position and to move the fork toward its working position.

4. In a planter, the combination with the check head frame, the seeder actuating device, the fork for operating said device and movable from a wire-discharging position to a normal wire-holding position, wire-holding devices supplemental to the fork and movable from a wire-discharging position to a normal working position, and an automatically acting lock for the supplemental wire-holder, of a laterally projecting 115 guide held stationary relatively to the frame and having its parts positioned substantially as described, relatively to the working positions of the fork and of the wire, to cause a section of the wire, while moving laterally 120 inward under longitudinal tension exerted at a distant point, to enter the fork when the latter is in its wire-discharging position and then move the fork toward its working position, the wire, while so moving carrying 125 130

the supplemental wire holder bodily into its working position.

5. In a planter, the combination with the check head frame, the seeder actuating device, the fork for operating said device and movable from a normal working position to a wire-discharging position, and movable means supplemental to the fork for holding the check wire in normal working position, 10 of a laterally projecting guide held stationary relatively to the frame and having an upper element and a lower element both extending longitudinally from points in front to points in rear of the fork and respectively 15 positioned as described relatively to the working positions of the wire and of the fork as set forth whereby said guide causes a section of the wire while moving laterally inward toward its working position and under longitudinal tension exerted at a distant point at an angle to the longitudinal lines of the machine, to enter the fork when the latter is in its wire-discharging position and to move the fork toward its working 20 position and cause the latter while so moving to also move said supplemental wire holder bodily into its working position.

6. In a planter, the combination with the check head frame, the seeder actuating device, the fork for operating said device and movable from a wire-discharging position to a normal wire-holding position, wire-holding devices supplemental to the fork and movable from a wire-discharging position to a normal working position, and an automatically acting lock for the supplemental wire-holder, of a laterally projecting guide held stationary relatively to the frame and having its parts positioned substantially 30 as described, relatively to the working positions of the fork and of the wire, to cause a section of the wire, while moving laterally inward under longitudinal tension exerted at a distant point, to enter the fork when the latter is in its wire-discharging position and then move the fork toward its working position and cause it while so moving to carry the supplemental wire holder bodily into its working position and also actuate 40 the lock for said holder.

7. In a planter, the combination with a check head frame, a seeder actuating device, a fork for operating said device and movable from a normal working position to a wire-discharging position, and movable means supplemental to the fork for normally holding the check wire in working position, of a check wire guide extending laterally from the frame, and comprising an upper element 50 and a lower element both stationary relatively to the frame and extending from points in front to points in rear of the fork and arranged to provide between them a passageway permitting a section of check wire to move bodily laterally therethrough 55

and to guide said wire section laterally into the fork when the latter is in discharging position and also guide the wire while moving the fork to normal working position, the entrance into the fork through which the 70 wire passes being arranged to intersect the aforesaid passageway.

8. In a planter, the combination with the check head frame, a seeder actuating device, and a fork for operating said device movable 75 from an approximately vertical working position to an approximately horizontal wire-discharging position, of a guide having a laterally disposed passageway, said guide comprising two elements both stationary relatively to the frame, one above and the other below the said passageway for the wire, the lower element having a downwardly turned outer extremity and the upper element having an upwardly turned outer extremity, 80 and the two elements being arranged as described whereby said passageway has an outer part which widens vertically outward and an inner part which widens vertically inward, and said fork when in its discharg- 85 ing position having its entrance in the vertically narrowed part of said passageway.

9. In a planter, the combination with the check head frame, the seeder actuating device, the fork for operating said device movable from its normal working position to a wire-discharging position, of a check wire guide stationary relatively to the said frame and comprising an upper element and a lower element with a horizontally disposed 100 passageway between them and arranged as described relatively to the fork when in its discharging position to have an arm of the fork adjacent to its wire entrance positioned across the said passage, the fork being 105 adapted to swing with the wire relatively to both elements of the stationary guide.

10. In a planter, the combination with the check head frame, the seeder actuating device, the fork for operating said device, the 110 pulley holder mounted on the frame, and an automatically acting lock for said holder, of the laterally projecting guide having an upper element and a lower element both rigidly secured to the frame and extending 115 continuously from points in front to points in rear of the fork and arranged to provide a passageway for a section of the wire to move laterally between said elements and adapted to guide the wire into the fork when 120 in its discharging position and to also guide it while it is swinging the fork and the pulley holder to their normal position.

11. In a planter, the combination with the check head frame, the seeder actuating 125 device, the fork for operating said device, the pulley holder mounted on the frame, and an automatically acting lock for said holder, of the laterally projecting guide having an upper element and a lower element 130

both rigidly secured to the frame and extending continuously from points in front to points in rear of the fork and arranged to provide a passageway for a section of the 5 wire to move laterally between said elements and adapted to guide the wire into the fork when in its discharging position and to also guide it while it is swinging the fork and while the fork is moving the pulley holder to 10 its normal position.

12. In a planter, the combination with the check head frame and the seeder actuating device, of a check wire guide which is stationary relatively to the frame and has a 15 passageway adapted to permit a section of wire to be moved bodily laterally therethrough to its normal working position, said guide having two elements, one positioned above and the other positioned below 20 the said passageway, and a fork for operating the seed actuating device positioned between the front and rear ends of the stationary guide, and movable from a vertical position at the inner end of the said passageway to a wire-discharging position, said fork having a wire-engaging part situated across said passageway between the stationary guide elements when it is in said wire discharging position.

30 13. In a planter, the combination with the frame check head and the seeder-actuating device, of the laterally projecting wire guide, with a passageway through which a section of wire can be moved bodily laterally, said guide having a relatively short lower element below said passageway, and a relatively longer element above said passageway, both of which elements are rigid with the frame and are shaped to provide a 35 vertically flaring entrance to said passageway, and a fork for operating the seed actuating device positioned at the inner end of said passageway and between the front and rear ends of the guide, said fork being movable to a wire receiving position where its 40 end lies between the said stationary guide elements.

45 14. In a planter, the combination with the check head frame, and the seeder actuating device of a laterally projecting wire guide, having a fixed passageway adapted to permit a section of wire to move bodily laterally therethrough, said guide comprising two elements fixed in position relatively to 50 the frame, one element being below said passageway and the other element being above it and extending farther from the frame than the lower element, the outer extremities of said guide elements being inclined oppositely to provide a vertically flaring entrance to said passageway and the extremity of the upper element being adapted to be initially impinged on by a rising wire, and a fork positioned at the 55 inner end of said passageway and between 60

the front and rear ends of the said fixed guide elements and adapted to move to a wire-receiving position where its wire-receiving end is near the inner end of the flaring mouth of said passageway. 70

15. In a check head for corn planters, the combination of a frame, a pulley holder pivotally mounted thereon, a seed dropper shaft, a fork pivotally mounted thereon, and a pair of vertically spaced guides mounted 75 on the frame comprising U-shaped members having their terminals secured to the frame and their other portions disposed substantially horizontal to direct the check wire into the fork.

16. In a check head for corn planters, the combination of a frame, a pair of concaved wire guides mounted thereon, a pulley holder pivotally mounted on the frame, a spring catch for engaging the pulley holder 80 to retain the same in an operative position, a seed dropper shaft, a fork pivotally mounted on the shaft, and a self threading means comprising a pair of vertically spaced guides, each in the form of a bar bent to 85 substantially U-shaped formation with their terminals secured to the frame and their remaining portions disposed substantially horizontal and their outer ends diverging whereby to guide the check wire into the 90 fork, and whereby the fork and pulley holder may be elevated when the wire is moved into engagement with the concaved wire guides.

17. In a planter, the combination with the check head frame, the seeder actuating device, the fork for operating said device and movable from a normal working position to a wire-discharging position, and movable means supplemental to the fork for holding the check wire in normal working 100 position, of a laterally projecting guide held stationary relatively to the frame and having an upper element and a lower element both extending longitudinally from points in front to points in rear of the fork and 105 respectively positioned as described relatively to the working positions of the wire and of the fork as set forth whereby said guide causes a section of the wire while moving laterally inward toward its working position and under longitudinal tension exerted at a distant point at an angle to the longitudinal lines of the machine, to enter the fork when the latter is in its wire-discharging position and to move the fork toward 110 its working position and means for locking said fork and said supplemental wire holder in their operative position. 115

In testimony whereof I affix my signature in presence of two witnesses.

PHILIP H. BAXTER.
